PRODUCTION OF TEXTILE MATERIALS

Henry Dreyfus, London, England, and William Alexander Dickie and William Ivan Taylor, Spondon, near Derby, England, assignors to Celanese Corporation of America, a corporation of Delaware

Application November 19, 1930, Serial No. 496,798
In Great Britain January 8, 1930

8 Claims. (CL. 18—8)

- This invention relates to artificial filaments, yarns or threads and their production by the extrusion of spinning solution through jets, nozzles, or other spinning orifices and is an improvement in or modification of the invention described and claimed in U. S. application S. No. 389,412 filed 30th August, 1929 of which this application is a continuation in part, which application has issued as Patent No. 1,898,085.
- 5 In that specification processes and apparatus are described whereby the filaments, yarns or threads (hereafter referred to as "threads") are formed with a regular or systematic irregularity in denier by stretching or drawing the threads at 10 intervals, to amounts, and for periods corresponding with the frequency, degree, and length of the variations in denier required in the threads produced, such drawing or stretching proceeding continuously with the production of the threads.
- 15 Various methods are described for effecting the variable stretching required, as, for example, by passing the threads round a roller rotating with varying peripheral speed, which causes the threads to be drawn down from the jet at varying 20 velocities, or by periodically lengthening the path followed by the filaments or threads as they proceed from the spinning jet or nozzle to a winding or twisting and winding device.
- 25 The variation in denier produced according to 30 the invention may appear at regular long, or regular short intervals of length, or at regularly varying intervals, and variations of different degree or extent or both may appear at any desired intervals. Thus, for example, groups of irregularities may be produced in any desired order, always 35 with the object of producing a regular or systematic effect from the alternating or periodically returning irregularities of the denier.

An object of the present invention is to provide 40 a further means of drawing or stretching the threads to produce threads of variable denier as required, and according to one feature of the invention the threads after extrusion are drawn from the jet or nozzle at varying linear speeds by 45 passing them over a roller rotating with a peripheral speed higher than the speed of extrusion of the filaments, the frictional force exerted by the roller on the threads, and thereby the rate of drawing of the filaments, being caused to increase 50 and decrease periodically, whereby a more or less frequent regular or systematic variation in denier is imparted to the filaments or threads.

Thus, for example, the thread may be held in, or brought into frictional engagement with the 55 roller by one or more bars, hooks, or other mem-

bers moving across the path of the thread to increase and decrease periodically the arc of driving contact between the roller and the thread. The bar or bars, or other means, may be moved across the path of the thread in such a way as 5 to produce variations of any desired frequency, degree and length.

According to another method of varying the friction between the roller and the thread, the surface of the roller may be modified over parts 10 of its area so as to grip the thread to a varying extent. Thus, the roller may be roughened in places, as for example by sandblasting or etching or by the application to the roller of suitable rough material, such as sand or emery cloth or 15 the like. The thread may have a constant arc of driving contact, in which case the variation in denier is due to the varying frictional effort produced by the differently roughened parts of the roller, or the arc of contact may be varied also, 20 in the manner indicated above, to produce a more irregular variation in denier than is obtainable by either of the methods alone.

A further method consists in using a second roller adapted to be pressed intermittently on to 25 the feed roller so that the thread passing between the rollers is frictionally nipped to a varying extent, any desired degree of slip being effected by suitable choice of pressure between the rollers. The second roller may run idly, or may be positively driven at a speed the same as or different 30 from that of the feed roller. One or both of the rollers may have a surface which is roughened in parts as indicated above.

Before reaching the roller or rollers, the thread 35 may be passed through a tension device, as for example, of the well known "gate tension" type, by means of which the variation resulting from the action of the roller or rollers may be modified to a considerable degree. Moreover, by using an 40 adjustable tension device with means for automatically varying the tension imparted, the degree of modification effected may be automatically varied, and further considerable variation in denier imparted to the thread.

A further feature of the invention relates to the method described in the prior U. S. application S. No. 389,412 by which the threads are drawn or stretched by causing them to traverse a path of 45 varying length, after the extrusion of the filaments from the jet. The parent specification describes passing the threads over or under means such as a bar or bars, which move in such a manner as to constrain the thread to move along a 50 55

path periodically increasing or decreasing in length.

According to the present invention the length of filament path is varied by passing the filaments or threads through one or more hooked or looped members or the like carried by rods, levers or other suitable means, and reciprocating or oscillating said members relatively to the normal straight path of the filaments or threads so as to cause the threads to follow a path of varying length. Or the threads may be acted on by a single bar which moves across their path with any desired frequency and to any desired amount to give them a variation in denier. These bars or other members may be arranged to operate on a single thread only, but they may likewise be of sufficient dimensions or so operated to lengthen the paths of several threads simultaneously. Thus, a single oscillating or reciprocating bar may be of sufficient length to cross the path of several threads which are being produced at the same time and are proceeding to separate winding or twisting and winding devices. In this case, the bar may be carried by two or more rods actuated by as many cranks, eccentrics, or the like from a suitable driving mechanism.

For the purpose of imparting a variation in denier occurring at fairly short intervals, an eccentric or cam or a rotating member having two or more arms may be rotated so as to lift or depress the threads from the normal straight path between the spinning cell and the feed roller, it being possible by these means to stretch the threads with a far greater frequency than with oscillating or reciprocating devices. The tip of the eccentric or cam or of each arm of the rotating member may be grooved so as to ensure proper engagement with the threads.

In order to increase the range of effects which can be formed on the threads, two or more devices such as those above described may be used in conjunction, the several devices operating with different frequency and/or amplitude so that the variations in denier occur with a frequency and/or degree which varies along a length of the thread. Similarly, one or more of such devices may be used with other devices described in the parent specification with like effect. Such arrangements may be caused to produce a group of denier variations which repeats itself at more or less long intervals along the length of the thread.

In order to effect a greater lengthening of the path of the threads, particularly where the frequency of the operation is fairly high, the thread may be caused to pass one or more guides or guide-bars arranged at one or both sides respectively of the device employed. The closer these guide means are to the lengthening device, the greater the lengthening effected, because of the more acute diversion from the straight path of the thread achieved.

Such guides or guide bars may be replaced if desired by adjustable or variable tension devices as described earlier in the specification, in which case the said devices will perform the double function of imparting a tension to the thread, and limiting the portion of the path over which variation in length takes place.

Any suitable means may be used to control the speed and motion of the stretching devices above described, and the devices may be arranged to give a gradual, or more or less abrupt change from one denier to another as desired. All the jets or nozzles, whether in a single metier or ma-

chine, or in a series of such, which are required to produce the same quality of material have associated therewith devices which are driven or controlled in such a manner as to exert the same stretching action on all the threads of filaments extruded from the jets or nozzles.

In all the methods for producing a variation in denier by a periodical variation in stretch of the threads on their way from the jet to the feed roller, the feed roller may run at any desired speed with respect to the rate of extrusion, i. e. the feed roller may operate to wind the threads at any desired speed, whether greater than the rate at which they are extruded or otherwise.

The yarns or threads produced as described may be wound, or twisted and wound, for example by means of cap-spinning devices, or centrifugal boxes.

The yarns or threads of varying denier may be applied to the production of fabrics or articles of novel appearance, either alone, or with yarns or threads of other natural or artificial filaments or fibres which may be utilized to give any desired design or pattern.

The invention may be applied to the production of artificial filaments, yarns, or threads by either the dry or evaporative method, or the wet or coagulation method, whether using spinning solutions of cellulose acetate, or other organic derivatives of cellulose, or viscose, nitrocellulose, cuprammonium or other spinning solutions.

The invention will now be described in detail with reference to the accompanying drawing, but it is to be understood that this description is given by way of example only and is in no respect limitative.

Fig. 1 shows the lower part of a spinning cabinet, together with one form of apparatus for drawing filaments from the cabinet at a varying rate.

Fig. 2 shows another form of apparatus for drawing the filaments at a varying rate.

Fig. 3 shows apparatus according to a further feature of the invention for causing the filaments to follow a path of varying length, while Fig. 4 shows a detail of the apparatus shown in Fig. 3.

Figs. 5 and 6 show a further form of apparatus according to the invention.

Figs. 7 and 8 show a variation of the apparatus shown in Figs. 5 and 6.

Fig. 9 is a perspective view of a further device according to the invention.

Referring to Fig. 1, the spinning cabinet 10 is provided with an aperture 11, through which are drawn a number of filaments in the form of a thread 12. The filaments are led over, but not round a roller 13, from which they proceed to the guide 14 of a cap-spinning device 15, by means of which they are twisted and wound on to a bobbin 16. Two guides 17, 18, before and behind the roller 13, are mounted upon an arm 19 which is carried by a rod 20. The rod 20 slides in a guide 21, and is caused to reciprocate up and down by means of a connecting rod 22 attached to a crank pin 23 mounted on a rotating disc 24. As the rod 20 and arm 19 come into their lower position the guides 17 and 18 deflect the thread 12 to the position shown in the figure in dotted lines, so that the thread 12 contacts with the roller 13 over an increased arc of contact. This increases the frictional force between the filaments and the roller 13 and so varies the rate at which the filaments are drawn from the spinning cabinet 10, a corresponding reduction

taking place in the denier of the filaments. On the upward movement of the guides 17, 18, the friction between the thread 12 and the roller 13 is lessened, so that slip takes place, and the rate 5 of draw-down of the filaments is lessened. Thus, there results a variation in denier corresponding with the frequency and extent of movement of the guides 17, 18.

Fig. 2 shows a further form of apparatus for 10 drawing off the threads at a varying rate. Here the filaments 12 pass over and in contact with a frictional roller 25 and are nipped against the roller 25 by means of a roller 26. The roller 26 is carried upon an arm 27 pivoted about a point 15 28, a spring 29 being provided at the other end of the arm, the spring being alternately compressed and released by the rotation of a cam 30 about its axis 31. The alternate compression and release of the spring 29 gives rise to the alternate 20 relief and application of the weight of the roller 26. In this manner the force with which the filaments 12 are nipped against the roller 25 is caused to vary, with the result that the filaments are driven alternately faster and slower, and an 25 intermittent variation in denier is thereby imparted to the filaments or threads.

In the two forms of apparatus shown in Figs. 1 and 2 the roller 18 or 25 may be roughened over part of its surface, as for example by etching or 30 sand blasting, or by covering such part with suitable rough material such as sand or emery cloth or the like, so that the thread will be gripped by such roughened part of the roller with greater force than by the untreated part, whereby further variations in denier are imposed upon the thread. As stated, this roughening may be made use of in connection with the apparatus shown in Fig. 1 or Fig. 2, or even may be used by itself, the threads being merely passed over and in frictional 40 contact with such intermittently roughened roller, preferably making thereon a relatively large arc of frictional contact.

Referring to Fig. 3, this shows an apparatus 45 whereby the path of the filaments is caused alternately to increase and decrease in length. The filaments 12 coming from the slot 11 in the spinning cabinet 10 pass through two hooked members 31, over a guide 32 and round a feed roller and back guide 33. The hooked members 31 are 50 mounted on rods 34 sliding in rotatable guides 35, and terminate at their lower ends in sheaves 36, embracing two eccentrics 37 rotating on the same shaft 38. In this manner the hooked members 31 are caused to reciprocate relatively to the direct path of the filaments, from the slot 11 to the guide 32 which is shown in dotted lines, whereby the length of the path of the filaments is caused to vary intermittently. The guide 32 is 55 shown in this figure which limits the length of the path over which fluctuation takes place, and thereby increases the degree of fluctuation caused. A further guide may be provided if desired, between the spinning cabinet 10 and the first guide 31, and again if necessary, between 60 the two guides 31. If desired use may be made of one hooked member only instead of two, or again three or more hooked members may be used with as many co-acting stationary guides as may be desirable.

70 The form of hooked members 31 may be that of a simple pigtail guide mounted on the ends of the rods 34, or if desired a long looped member such as is shown in Fig. 4 may be used to control the path of two or more threads 12. Fig. 4 shows 75 clearly how the guide 31 may deflect the thread

12 above its direct path by engagement with the part 39, and below the direct path by engagement with the part 40. The threads are placed in, and if necessary removed from, the guide through the gap 41. Further, a large number of threads 12 5 may be produced, having some variations in denier, by using a single shaft 43 to drive a number of eccentrics along the whole length of a spinning machine producing a large number of threads. 10

Figs. 5 and 6 show a side view and an end view respectively of a device for producing rapid fluctuations of denier of the thread. A rotating member having three arms 45 mounted upon a boss 46 is caused to rotate about a shaft 47. As shown 15 in Fig. 6 the tips 48 of the members 45 are grooved so that the thread 12 is engaged by the said members and may not slip off the end in their rotation about the shaft 47. The members 45 lift the thread 12 from its normal straight path shown 20 in dotted lines, thereby causing variations in the length of the path followed by the thread, and correspondingly in the denier of the thread. In view of the number of arms 45, and the lightness of the rotating path the frequency of the variations in denier produced may be made relatively 25 high. More than three arms 45 may be used, with a corresponding increase in the frequency, though at the cost of the degree of fluctuation in denier. Guides 49, 50 are provided to limit the length of 30 path in which such deviation takes place.

Figs. 7 and 8 show a side view and an end view of a single lift cam 51 rotating about a shaft 52 and having groove ends 53 for the purpose of retaining the thread. Such a cam may be used in the same manner as the three armed member shown in Figs. 5 and 6, the degree of variation obtainable with such a single lift member being greater than that obtainable with a three armed member. Similarly, a double lift member having two arms may be used with an increase of 40 frequency, but without any loss in the degree of fluctuation. Fig. 9 shows a perspective view of a device whereby the frictional pull on the filaments 45 is alternately increased and decreased. The roller 42 mounted upon shaft 43 is modified over parts of its surface by the application thereto of emery cloth 44. The thread passing over the roller is subjected to varying frictional effort produced by the differently roughened parts of the roller thus 50 producing a variation in denier.

It will be understood that two or more of the devices shown in Figs. 5-8 may be used in conjunction, the devices rotating at the same or at different rates to produce regular or irregular, or cyclically occurring variations in the denier of the thread. 55

What we claim and desire to secure by Letters Patent is:—

1. Process for the production of artificial filaments, said process comprising forming the filaments by extrusion, and applying to the filaments continuously with their extrusion a continual and periodically varying frictional force so as to draw the filaments from the point of extrusion at varying linear speeds in the course of their production, whereby a variation in denier is imparted to the filaments. 60

2. Process for the production of artificial filaments of cellulose acetate, said process comprising extruding a solution of cellulose acetate in the form of filaments, and applying to the filaments continuously with their extrusion a continual and periodically varying frictional force so 65 70 75

- as to draw the filaments from the point of extrusion at varying linear speeds in the course of their production, whereby a variation in denier is imparted to the filaments.
5. Process for the production of artificial filaments, said process comprising forming a number of filaments by extrusion of a spinning solution into an evaporative medium, and applying to the filaments continuously with their extrusion a continual and periodically varying frictional force so as to draw the filaments from the point of extrusion at varying linear speeds in the course of their production, whereby a variation in denier is imparted to the filaments.
10. 6. Process for the production of artificial filaments, said process comprising forming a number of filaments by extrusion of a spinning solution of cellulose acetate into an evaporative medium, and applying to the filaments continuously with their extrusion a continual and periodically varying frictional force so as to draw the filaments from the point of extrusion at varying linear speeds in the course of their production, whereby a variation in denier is imparted to the filaments.
15. 7. Apparatus for the production of artificial filaments, comprising a spinning jet, a roller over which the filaments pass on leaving said jet, means for rotating the roller at a peripheral speed higher than the speed of extrusion of the filaments, and means for periodically increasing the arc of contact between the roller and the filaments, so as to vary the degree of frictional force 5 exerted by the roller on the filaments and to draw the filaments at varying linear speeds in the course of their production, whereby a variation in denier is imparted to the filaments.
10. 8. Apparatus for the production of artificial filaments, comprising a spinning jet, a roller over which the filaments pass on leaving said jet, means for rotating the roller at a peripheral speed higher than the speed of extrusion of the filaments, a second roller adapted to nip the filaments 15 against the first roller, and means for varying the force with which the filaments are so nipped, so as to vary the degree of frictional force exerted by the roller on the filaments and to draw the filaments at varying linear speeds in the course of 20 their production, whereby a variation in denier is imparted to the filaments.
20. 9. Apparatus for the production of artificial filaments, comprising a spinning jet, a roller over which the filaments pass on leaving said jet, and means for rotating the roller at a peripheral speed higher than the speed of extrusion of the filaments, said roller being provided with a surface which is modified in parts to give a varying coefficient of friction between the roller and the filaments, so as to vary the degree of frictional force exerted by the roller on the filaments, and to draw the filaments at varying linear speeds in the course of their production, whereby a variation in 25 denier is imparted to the filaments.
25. 10. Apparatus for the production of artificial filaments, comprising a spinning jet, a roller over which the filaments pass on leaving said jet, means for periodically varying the degree of frictional force exerted by the roller on the filaments so as to draw the filaments at varying linear speeds in the course of their production, whereby a variation in denier is imparted to the filaments.
30. 11. Apparatus for the production of artificial filaments, comprising a spinning jet, a roller over which the filaments pass on leaving said jet, means for periodically varying the degree of frictional force exerted by the roller on the filaments so as to draw the filaments at varying linear speeds in the course of their production, whereby a variation in denier is imparted to the filaments.
35. 12. Apparatus for the production of artificial filaments, comprising a spinning jet, a roller over which the filaments pass on leaving said jet, means for periodically varying the degree of frictional force exerted by the roller on the filaments so as to draw the filaments at varying linear speeds in the course of their production, whereby a variation in denier is imparted to the filaments.
